UNITED STATES PATENT OFFICE.

JOHN B. CLOT, OF SAN FRANCISCO, CALIFORNIA.

AIR OR GAS COMPRESSING PUMP.

SPECIFICATION forming part of Letters Patent No. 325,395, dated September 1, 1885.

Application filed May 13, 1885. (No model.)

To all whom it may concern:

Be it known that I, JOHN B. CLOT, a citizen of the United States, and residing at the city and county of San Francisco, and State of California, have invented a new and useful Improvement in Pumps for Compressing Air or Gas, more especially for such pumps as are used in ice or refrigerating machines, of which the following is a specification.

10 My invention relates to improvements in air or gas compressing pumps in which a lubricating-fluid is contained within the cylinder to be lubricated, the fluid being in large quantities, so that the supply of the lubricant is used over and over again.

15 The object of this invention is to lubricate the cylinders, pistons, and piston-rods of air or gas compressing pumps, and at the same time to cool the lubricating-fluid, so that it shall aid 20 in keeping the cylinder cool from the effects of compressing air or gas, and in accomplishing this to use the least practicable quantity of lubricant consistent with a proper reduction of friction of wearing parts; also, to have a 25 continuous circulation of the lubricating-fluid from one cylinder to another in two combined single-acting compressing-pumps for the purpose before stated, and, in addition, to cool the lubricating-liquid by means of surface-contact 30 in passing from one cylinder to the other. By this method of construction and arrangement of parts a much less quantity of lubricant is required, and while protected from the influence of the atmosphere is yet under but little 35 more than atmospheric pressure.

35 The drawing herewith presented and forming a part of this specification, will enable any one skilled in the art to which my invention appertains to construct a gas or air compressing pump which will easily perform the duties 40 required of it, and with the least care be kept well lubricated and cooled in its internal acting parts.

45 In the drawing, A A are the two single-acting inverted cylinders with pistons B B, piston-rods C C, inlet and outlet valves D D D D for the air or gas which is to be compressed or is being compressed; E E, the stuffing-boxes for packing the piston-rods; F, a connecting-channel between the lower ends of the two cylinders, and G a chamber surrounding a part 50 of the channel, through which chamber G

passes the gas or air on its way to the pump to be compressed. These pipes connecting the chamber G to the inlet-valves of the pump may 55 be of any convenient and desired form which is well known.

The pipe H leading from the chamber G to the refrigerator is such as is in common use 60 for this purpose.

The cylinders, pistons, and valves of this pump may be of any well-known construction adapted for the purpose, the principal feature of my invention being the connecting together the two lower ends of the single-acting cylinders, forming an unobstructed communication one with the other, so that the movement of the pistons being coincident but in opposite directions the space between the under sides of the pistons will remain practically constant in 70 volume, and any fluid or liquid occupying this space will be alternately drawn and forced into each cylinder when being displaced from the other. This space is filled with any lubricating-liquid adapted for the purpose, and in the 75 operation of the pistons will follow each piston in its upward movement, thoroughly lubricating the inner walls of the cylinders and abstracting from them the heat which the walls have received from the compressed gas or air. 80 As the piston descends, it forces the lubricant under it through the connecting-channel F, which is surrounded by the chamber G, (through which is passing the cold gas or air on its way to the inlet-valve of the pump,) thus releasing 85 the heat which the lubricating-liquid had absorbed from the walls of the cylinder which it just left, and preparing it to lubricate and absorb the heat from the cylinder which it enters on the upward stroke of the piston in the 90 second cylinder.

The pistons may be operated by any of the well-known means, as by a shaft having cranks set opposite each other and having an inverted steam-cylinder between them, in which case 95 the connecting-channel F will be carried around the steam-cylinder, or by a horizontal steam-cylinder, or by a beam which may be moved by a crank on a distant shaft.

Any loss by leakage of the lubricant around the piston-rods and through the stuffing-boxes can be made good through the pipe and cock J, into the funnel top of which the required amount can be poured, this pipe reaching a 100

little higher than the under side of the pistons when at their highest point.

Should the pistons B B leak some of the gas or air when at its greatest degree of compression, thus creating an undue pressure on the lubricating-fluid, I provide the lightly-loaded valves K K, which will rise with any predetermined pressure and allow the gas or air to return above the pistons during the descent so when the gas or air above them is at its lowest tension.

The proportions of the chamber G to the channel F will be determined by the comparative temperatures of the compressed and un-compressed gases passing through, or of such a quantity of cooling surface in G that the heat absorbed by the lubricant from the walls of the cylinder may be easily taken up by the gas or air passing through the chamber G.

I am aware that prior to my invention pumps have been lubricated by liquid which was contained in each cylinder by itself and into which the piston dipped at the bottom of its stroke, and also that pistons and cylinders have been lubricated by passing a small quantity upward

or downward through the piston at each stroke; but these I do not claim.

What I claim, and desire to secure by Letters Patent, is—

1. In a gas or air compressing pump, the combination of the two cylinders A A, the pistons B B, with a connecting-channel, F, the inlet and outlet-valves D D D D, the chamber G, the pipe and cock J, and the valves K K, substantially as shown and described, and for 35 the purposes set forth.

2. In an air or gas compressing pump, the combination of the cylinder, piston, connecting-channel, and surrounding chamber and conduits, with a body of lubricating-fluid by 40 which the heat is abstracted from the walls of the cylinders and transferred to the air or gas which is passing through the chamber on its way to the pumps to be compressed, all substantially as shown and described, and for the 45 purpose set forth.

JOHN B. CLOT.
